(57) **CLAIM**

The ornamental design for a wireless amplifier system, as shown and described.

DESCRIPTION

A portion of the disclosure of this patent document contains material which may be protected by copyright. The copyright owner has no objection the facsimile reproduction by anyone of the patent document or the patent disclosure, as it appears in the Patent and Trademark Office patent file or records, but reserves all other copyright rights whatsoever.

FIG. 1 is a reference view of the wireless amplifier system, embodying my new design, shown with both components in use with speakers and a receiver;

FIG. 2 is a second reference view thereof, showing the two system components;

FIG. 3 is a front view of the first component thereof, shown separately for ease of illustration;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front view of the second component thereof, shown separately for ease of illustration;

FIG. 10 is a rear view thereof;

FIG. 11 is a left side view thereof;

FIG. 12 is a right side view thereof;

FIG. 13 is a top plan view thereof; and,

FIG. 14 is a bottom plan view thereof.

The broken line showing of the cords, receiver and speakers is included for the purpose of illustrating environmental structure and forms no part of the claim.
